UNITED STATES PATENT OFFICE.

JOSE LOUIS CASTILLO, OF SAN FRANCISCO, CALIFORNIA.

SERPENTINE-SHOOTER.

Specification of Letters Patent. Patented Apr. 24, 1917.

1,224,112.

Application filed September 11, 1916. Serial No. 119,445.

To all whom it may concern:

Be it known that I, JOSE LOUIS CASTILLO, a citizen of Guatemala, residing in the city and county of San Francisco and State of California, have invented new and useful Improvements in Serpentine-Shooters, of which the following is a specification.

This invention relates to a gun, and is particularly adapted to shoot rolls of paper ribbon known as "serpentine."

Referring to the accompanying drawing which forms a part of this specification:—

Figure 1 is a perspective view of the invention.

Fig. 2 is a cross section taken on line α — α Fig. 1.

The gun comprises a stock 1 and a barrel 2 in the form of a pistol. The barrel is provided with a longitudinal dove-tail groove 3 in its upper face in which is mounted a slide 4. Upon the rear end of the slide is secured a holder 5 to the sides of which are secured arms 6. Arms 7 project from each side of the barrel at the end thereof, and elastic bands 8 respectively connect each arm 7 with an arm 6 at the same side of the gun barrel. A stop 9 is located at the forward end of the groove 3 to limit the forward movement of the slide 4, and a stop 10 is located at the rear end of the groove to limit the rearward movement of the slide. A ring 11 is connected to the rear of the holder 5 by means of which the holder and slide are drawn backward along the barrel.

2. A clip 12 is secured to the stock 1 to which the inner end of a serpentine roll is attached, while the serpentine itself is placed on the slide 4 within the holder 5 to be shot by the gun.

40 In order to shoot the serpentine from the gun, the stock of the gun is held in the hand and the barrel aimed in the direction in which it is desired to shoot the serpentine: the ring 11 is grasped and the holder and slide and the serpentine are drawn backwardly along the barrel against the tension of the elastic bands 8, the ring is then released and the holder and slide and the serpentine are drawn forward rapidly by the

bands 8 until the slide and holder are arrested by the stop 9 at the forward end of the barrel, whereupon inertia discharges the serpentine forwardly beyond the forward end of the barrel, the serpentine unwinding as it travels forwardly and the rear end 55 thereof being held captive by the clip 12.

Having thus described my invention, what I claim and desire to secure by Letters Patent is:—

1. A gun including a stock having a barrel, said barrel having a longitudinal dove-tail groove in its upper face, a slide having a dovetail projection engaged in said groove, a holder secured to the upper face and rear end of the slide and having a curved front face extending on opposite sides of the slide whereby to allow a serpentine reel to seat on a side thereof on the upper face of the slide and have its periphery engaged with said curved front face of the holder, a ring connected to the rear end of the holder, a rigid stop on the barrel at the inner end of the groove, means to project the slide outwardly, and a clamping clip secured to a side of the stock, said holder having a flat upper face so as to allow an end of the serpentine to be arranged thereover and connected to said clip.

2. A gun including a stock and a barrel, a holder slidably connected to the barrel, said holder having a horizontal bottom to receive one flat side face of a serpentine reel and having a vertical curved wall to engage the periphery of the reel, whereby to hold the reel in horizontal position with its side faces parallel to the barrel, and a clamping clip secured to the stock, said vertical curved wall of the holder being formed so as to allow one end of the serpentine to be passed therebeyond and clamped by the clip, against the stock.

In testimony whereof I have hereunto set my hand in the presence of two subscribing witnesses.

JOSE LOUIS CASTILLO.
